United States Patent Office

Des. 178,936
Patented Oct. 9, 1956

178,936

COMBINED CEMETERY GATE AND FENCE UNIT OR THE LIKE

Glanville W. Smith, Cold Spring, and Roland A. Bartholemey, St. Cloud, Minn., assignors, by mesne assignments, to J. R. Whitmer, Bowling Green, Ky.

Application September 14, 1954, Serial No. 32,285

Term of patent 14 years

(Cl. D28—1)

The figure is a perspective view showing a combined cemetery gate and fence unit or the like embodying our design.

The side of the design opposite that shown in the drawing is identical in appearance to the side shown.

We claim:

The ornamental design for a combined cemetery gate and fence unit or the like, as shown and described.
